CLAIM

The ornamental design for an interchangeable ornament ring, as shown and described.

DESCRIPTION

FIG. 1 is a front perspective view of an interchangeable ornament ring showing my new design;

FIG. 2 is a front view thereof; and

FIG. 3 is a back view thereof; and

FIG. 4 is a right side view thereof; and

FIG. 5 is an left side view thereof; and

FIG. 6 is a top view thereof; and

FIG. 7 is a bottom view thereof; and,

FIG. 8 is another front perspective view thereof.

The broken lines are for illustrative purposes only and form no part of the claimed design.
